UNITED STATES PATENT OFFICE

WILLIAM C. TREGONING, OF WAUWATOSA, WISCONSIN, ASSIGNEE TO CUTLER-HAMMER, INC., OF MILWAUKEE, WISCONSIN, A CORPORATION OF DELAWARE

ELECTRIC SWITCH

Application filed January 31, 1931. Serial No. 512,608.

This invention relates to improvements in electric switches.

An object of the invention is to provide a switch mechanism of simple, rugged and durable construction, the parts of which are not likely to become deranged when in use.

Another object is to provide a switch of the aforementioned character the parts of which may be quickly and inexpensively assembled.

Another object is to provide movable and stationary switch contacts and terminal elements of improved form.

Other objects and advantages of the invention will hereinafter appear.

The accompanying drawing illustrates certain embodiments of the invention which will now be described, it being understood that the embodiments illustrated are susceptible of modification in certain details thereof without departing from the scope of the appended claims.

In the drawing, Figure 1 is an enlarged perspective view, in separated relation, of a single-pole or single-circuit-controlling switch constructed in accordance with my invention.

Fig. 2 is a bottom plan view of the switch shown in Fig. 1.

Fig. 3 is a vertical sectional view, on the line 3—3 of Fig. 2.

Fig. 4 is a plan view of the sheet metal blank from which the switch housing may be formed.

Fig. 5 is a bottom plan view of a three-position or multiple-circuit-controlling switch constructed in accordance with my invention.

Fig. 6 is a vertical sectional view, on the line 6—6 of Fig. 5, and

Fig. 7 is a horizontal section, on the line 7—7 of Fig. 6, but showing a different full-line position of the bridging contactor of the switch.

Referring first to Figs. 1 to 4, the numeral 10 designates a support for the stationary contact and wiring terminal elements of the switch, said support preferably consisting of a flat punched plate of fiber-board or other suitable insulating material. Spaced longi-

tudinally of plate 10 are a pair of substantially rectangular openings 11 and 12.

The stationary contacts of the switch consist of a pair of metal studs 13 and 14 (preferably solid, as shown)—said studs having parallel flat sides and curved vertical edges as shown, so that the same are of substantially elliptical form in horizontal cross section. The vertical edges of said studs are cut away for a portion of the length thereof to provide shoulders 13^a, 14^a which are adapted to seat against the upper surface of plate 10, and to provide shanks 13^b, 14^b which are adapted to penetrate and fit fairly snugly within the openings 11 and 12.

Underlying plate 10 are a pair of identically formed terminal members 15 and 16, said members having horizontal portions 15^a, 16^a provided with openings 15^b, 16^b which are aligned with the openings 11, 12 to accommodate the shanks 13^b, 14^b aforementioned,—said shanks having the ends thereof upset or riveted over the horizontal portions 15^a, 16^a (as shown in Figs. 2 and 3) to rigidly and permanently secure the contact and terminal members to each other and to plate 10. Members 15, 16 are preferably provided with integral vertically extending portions 15^c, 16^c, said portions 15^c, 16^c being tapped as shown for reception of the binding screws 17 of well known form.

The opposite edges of plate 10 are provided with notches 18 and 19 offset longitudinally of the plate relatively to each other, and a notch 20 of relatively greater width is provided at one end of the plate.

A one-piece sheet metal housing for the switch parts is provided,—said housing comprising a flat top wall 21, parallel side walls 22 and 23, and two pairs of half-end walls 24 and 25. The housing may be formed from the blank illustrated in Fig. 4, the points of bending being indicated by dotted lines.

Thus the side walls 22, 23 are bent downwardly at right angles to top wall 21, and the half-end walls 24, 25 are bent inwardly at right angles to walls 22, 23. Top wall 21 is of slightly greater length than the main body of the blank whereby the perforated

70

75

80

85

90

95

100

lugs 26, 27 may be provided to facilitate attachment of the housing to a suitable support,—the half-end portions 24, 25 in the blank being separated from lugs 26, 27 by the notches as shown to facilitate the aforementioned bending operation.

The housing is provided with integral lugs 28, 29, 30 and 31 to register with the notches 18, 19 and 20 in plate 10, said lugs being bent inwardly over said plate as shown in the other figures to secure said parts to each other. The top wall of the housing is provided with an opening 32 to provide clearance for the operating lever 33 of the switch,—said lever being pivotally supported, as by a pin 34 which penetrates the aligned openings 35, 36 in side walls 22, 23. One end of said pin is headed, and the other end is swaged or otherwise enlarged after assembly thereof with respect to lever 33 and the walls 22, 23 of the housing.

The inner end of lever 33 is of reduced diameter to provide the annular shoulder 37 and to provide the integral hollow stud or rivet 38. Strung upon stud 38 is an insulating washer or plate 39 having a downwardly struck annular flange 39^a which is accommodated within the relatively large opening 40 in the flat portion 41 of a resilient sheet metal contactor. Also strung upon stud 38 beneath said portion 41 is an insulating washer 42 having an upwardly struck annular flange 42^a which is complementary to the flange 39^a for insulating portion 41 from the actuating lever 33,—the hollow stud 38 being upset over the metal washer 43 to rigidly secure the aforementioned parts to each other.

Extending downwardly and inwardly from opposite sides of portion 41 of the contactor are a pair of flat resilient arms 44 and 45, the lower edges 44^a, 45^a of which are curved as shown, and the end portions 44^b, 45^b of which arms are bent in an arc concentric to the pivot pin 34. The arrangement is preferably such that the edges 44^a, 45^a are normally spaced from each other at the mid-points thereof and the same flare away from each other toward opposite sides 50 of the respective arms.

As shown in Fig. 3, the curved edges 44^a, 45^a are adapted to resiliently engage the stud contact 14 in both the on and the off positions of the switch. The handle portion of lever 33 preferably abuts against the opposite side walls of the opening 32 in top portion 21 of the housing,—one wall 32^a (Figs. 1 and 4) of said opening being formed as shown to avoid any possibility of engagement of the contactor with the housing in the on (or dotted line) position of the switch.

As will be apparent from Fig. 3, upon manual operation of lever 33 toward the left from the position thereof as illustrated, the edges 44^a, 45^a have a camming engagement

with stud contact 14 to spread the arms 44, 45, so that when the mid-points of said edges pass the center line of said stud, the energy stored in said arms is released to cause snap movement of said edges into engagement with stud contact 13 to bridge the latter and stud 14. Obviously a similar movement of lever 33 in the reverse direction will result in snap movement of the edges 44^a, 45^a to the opposite side of stud 14 after the mid-points of said edges have passed the center line of said stud. 70

While the double-arm form of contactor as illustrated is preferred because it provides an extremely well-balanced movement of the switch, it is to be understood that a somewhat similar result may be obtained if one of the arms 44 or 45 is omitted. 75

The switch parts illustrated in Figs. 5, 6 and 7 are in general quite similar to those aforementioned except that one contact and terminal member is added and the contactor is specially formed for cooperation with the contacts to provide a three-position or multiple-circuit-controlling switch. 80

In Figs. 4, 5 and 6 the insulating plate 46 is like the plate 10 aforementioned, except that three rectangular openings 47, 48 and 49 are provided,—the opening 47 being preferably located in the same position as opening 11, with the openings 48 and 49 arranged at equally spaced intervals longitudinally of plate 46. The stud contacts 50, 51 and 52 are identical with the studs 13, 14 aforementioned and the terminal members therefor are of the aforementioned character. The structure and manner of assembling lever 33 is the same in both forms of the switch mechanism. As best shown in Fig. 6, however, the arms 53 and 54 of the contactor are reduced in width or cut away on one side of the center line of the lever, to cooperate with the less widely spaced stud contacts and to provide for vertical positioning of the lever in an intermediate position of the switch. 95

The switch housing is of the same form as aforementioned, except that the opening 32 in top wall 21 may be completely circular, since due to the reduced width of the contactor there is no liability of engagement thereof with the right-hand wall of the housing in the right-hand position of the switch contactor (as shown in dotted lines in Fig. 6 and in full lines in Fig. 7). Figs. 6 and 7 likewise show in dotted lines the off position of the contactor at the left-hand side of contact stud 52. 105

Each of the switches illustrated is particularly adapted for controlling the circuit or circuits of the dash lights of automobiles. In Figs. 1 to 3 it may be assumed that the terminal of stud contact 13 will be connected to a battery or other source of current supply,—the other switch terminal being connected with the lamp whose circuit is to be controlled thereby. In Figs. 5, 6 and 7 it may be as- 115

sumed that the terminal of the intermediate stud contact is connected with the source of current supply whereas the terminals of stud contacts 50 and 52 are connected with the

5 respective lamps for directly and indirectly illuminating the automobile dash board or panel. Obviously, however, the switches illustrated are adapted for control of the circuits of other types of translating devices of 10 relatively low current carrying capacity.

The top wall 21 of the respective switch housings may be provided with suitable legends to indicate the circuit controlling effect provided by the switch in its several positions, 15 such legends being of particular value in connection with the multiple-circuit-controlling switch of Figs. 5 to 7 to facilitate proper assembly of the lever and contactor with respect to the switch housing,—the aforementioned lugs and notches insuring proper assembly of the insulating base plate with respect to the housing.

What I claim as new and desire to secure by Letters Patent is:

25 1. In an electric switch, in combination, an insulating base, a plurality of stud contacts secured to said base and projecting upwardly from the latter, a bridging contactor pivotally supported independently of said base, 30 said contactor having resilient arms the inwardly extending curved edge portions of which are adapted to straddle said stud contacts, and said contactor being movable with a snap action to opposite sides of one of said 35 stud contacts for bridging engagement with or disengagement from other of said stud contacts selectively.

2. In an electric switch, in combination, an insulating base, a plurality of equally spaced 40 stud contacts secured to said base and projecting upwardly from the latter, a contactor pivotally supported independently of said base, said contactor having a resilient arm the inwardly extending curved edge portion of 45 which is arranged at one side of said stud contacts and biased into engagement with the latter, said contactor having a number of positions in which it engages each of a pair of adjacent stud contacts and another position 50 in which it engages only one of said stud contacts, and means other than said base and said stud contacts for limiting movement of said contactor in opposite directions respectively.

3. In an electric switch, in combination, a 55 sheet metal housing of rectangular form having a top wall and pairs of vertical side and end walls formed integrally therewith, a switch lever pivotally supported by said side walls and having a handle portion extending 60 outwardly through an opening provided in said top wall, a contactor rigidly secured to but insulated from said lever, said contactor comprising a punched plate of resilient sheet metal bent into the form of a loop having a 65 lower end opening which is of gradually in-

creasing width toward the respective side edges of said contactor, a flat punched plate of insulating material secured to the lower end of said housing, and a plurality of contact members secured to said insulating plate and projecting upwardly into the path of said contactor.

4. In an electric switch, in combination, a sheet metal housing of rectangular form having a top wall and pairs of vertical side and end walls formed integrally therewith, a switch lever pivotally supported by said side walls and having a handle portion extending outwardly through an opening provided in said top wall, a contactor rigidly secured to but insulated from said lever, said contactor comprising a punched plate of resilient sheet metal bent into the form of a loop having a lower end opening which is of gradually increasing width toward the respective side edges of said contactor, a flat punched plate of insulating material secured to the lower end of said housing, a plurality of contact members of substantially elliptical form in cross section extending upwardly from said insulating plate into the path of said contactor, wiring terminal members underlying said insulating plate, said terminal members and said insulating plate having substantially rectangular openings formed therein, and said contact members having reduced shanks of rectangular form adapted to penetrate said openings, said shanks being upset over said terminal members to rigidly and permanently secure all of said parts to each other.

5. In an electric switch, in combination, a punched plate of insulating material, a wiring terminal member having a horizontal portion underlying said plate and a vertical portion laterally offset from said horizontal portion and tapped to receive a binding screw, said plate and said horizontal portion having aligned angular openings formed therein, and a contact comprising a stud having a portion projecting upwardly from said plate and a reduced shank of angular cross section adapted to penetrate the openings aforementioned, the end of said shank being upset over said horizontal portion to rigidly and permanently secure all of said parts against movement relatively to each other.

6. In an electric switch, in combination, a punched plate of insulating material, a plurality of wiring terminal plates having horizontal portions underlying said plate and vertical portions laterally offset from the respective horizontal portions and tapped to receive binding screws, said plate and said horizontal portions having aligned angular openings formed therein, a plurality of stationary contacts comprising vertical studs having portions thereof projecting upwardly from said plate and reduced shanks of angular cross section adapted to penetrate the openings aforementioned, the ends of said

shanks being upset over said horizontal portions to rigidly and permanently secure all of said parts against movement relatively to each other, and a resilient contactor having 5 arms straddling the upwardly projecting portions of said contacts and movable selectively into or out of bridging engagement with the latter.

7. In an electric switch, in combination, a 10 pivoted actuating lever, a hollow stud formed integrally with the lower end of said lever, a sheet metal contactor and a washer strung upon said stud, a pair of insulating plates arranged on opposite sides of said contactor, 15 said plates having abutting annular flanges to insulate said contactor from said stud, the lower end of said stud being riveted over said washer to secure said parts in assembled relation to each other, and said contactor 20 having oppositely disposed resilient arms provided with curved end edges, the lower end portions of said arms being bent inwardly toward each other, whereby said curved end edges are arranged in spaced alinement, 25 for the purpose set forth.

8. In combination, a contactor for electric switches comprising a punched plate of resilient sheet metal, said plate being bent to provide a flat intermediate portion of substantially rectangular contour and flat arm 30 portions of like form extending downwardly and inwardly with respect thereto, means providing a fixed axis of oscillation for said contactor, said arm portions having arcuate 35 lower edges and the lower ends of said arm portions having arcuate bends concentric with said axis of oscillation whereby said edges are opposed to each other for cooperative bridging engagement with the stationary 40 contacts of the switch.

9. In a three-position switch, in combination, an insulating base, three stud contacts secured to said base and projecting upwardly therefrom, said contacts being arranged 45 in parallel relation and being equally spaced from each other longitudinally of said base, the end contacts of the group being unequally spaced from the respective ends of the base, a combined switch contactor and actuating 50 lever pivoted independently of said base, said contactor having a resilient arm the in-turned lower edge portion of which is adapted to bridge the center contact and one of the end contacts in one extreme position of 55 said lever, said contactor being adapted to bridge the center contact and the other of said end contacts in the intermediate position of said lever, and said contactor being adapted to engage the last mentioned end 60 contact only in the opposite extreme position of said lever.

10. In a three-position switch, in combination, an insulating base, three stud contacts secured to said base and projecting upwardly 65 therefrom, said contacts being arranged in

parallel relation and being equally spaced from each other longitudinally of said base, the end contacts of the group being unequally spaced from the respective ends of the base, a combined switch contactor and actuating 70 lever pivoted independently of said base, said contactor having a resilient arm the in-turned lower edge portion of which is adapted to bridge the center contact and one of the end contacts in one extreme position of said lever, said contactor being adapted to bridge the center contact and the other of said end contacts in the intermediate position of said lever, said contactor being adapted to engage the last mentioned end contact only in the opposite extreme position of said lever, said in-turned lower edge portion of said contactor being arranged in an arc concentric with the pivot point of said lever, and the main body of said contactor arm being offset 80 longitudinally of said base with reference to the longitudinal center line of said lever.

11. A contact for electric switches comprising a solid metal stud having parallel flat sides and rounded vertical edges, said edges being cut away for a portion of the length of said stud to provide horizontal shoulders and a shank of rectangular form in cross section, the end of said shank being deformable to provide for rigid attachment of said stud 95 to a suitable support.

In witness whereof, I have hereunto subscribed my name.

WILLIAM C. TREGONING.
